SHUTTLE BOX BINDER FOR LOOMS

Filed Oct. 19, 1945

UNITED STATES PATENT OFFICE

2,420,994

SHUTTLE BOX BINDER FOR LOOMS

William Languirand, New Bedford, Mass., assignor to Textile Research Co., a corporation of Massachusetts

Application October 19, 1945, Serial No. 623,298

4 Claims. (Cl. 139—185)

1

This invention relates to a loom, more particularly to the back binder for the shuttle box of the loom.

The back binder is usually pivotally mounted and resiliently pressed into the shuttle box at a location to be contacted by the shuttle when the shuttle enters the box. The resilient pressure is usually through the protection rod. The back binder is sometimes made in such a manner as to have inherent resiliency by means of a slot extending lengthwise thereof. Sometimes the back binder is covered with some resilient material. The exact position of its contacting surface is somewhat indeterminate.

One of the objects of this invention is to provide an arrangement for nicely adjusting the shuttle contacting surface of the back binder to provide maximum area of contact between shuttle and binder.

Another object of the invention is to provide for better checking of the shuttle with less binder pressure.

Another object of the invention is to reduce wear on both shuttle and back binder.

Another object of this invention is to provide a means for adjusting the position of a movable part of a back binder such for instance as a resilient tongue so that the surface of the back binder which contacts the shuttle may be varied as to its position relative to all of the rest of the shuttle box.

More specifically an object of this invention is to provide a micrometer adjustment of this movable part of the back binder such for instance as by a threaded member or screw.

With these and other objects in view, the invention consists of certain novel features of construction, as will be more fully described and particularly pointed out in the appended claims.

In the accompanying drawings;

Fig. 1 is a rear elevation of the back binder;

Fig. 2 is a top plan view thereof;

Fig. 3 is a perspective view of a fragmental portion of the loom lay illustrating the back binder in position relative to the back wall of the shuttle box and picker and picker stick;

Fig. 4 is a section on line 4—4 of Fig. 2;

Fig. 5 is a section on line 5—5 of Fig. 2.

In proceeding with this invention, I mount an abutment in the movable portion of the back binder and thread a member through the body portion of the back binder to engage this abutment so as to swing this movable portion to cause its surface which engages the shuttle to be forced into the path of the shuttle or removed from the shuttle path as occasion may require.

With reference to the drawings, 10 designates generally the body of the back binder which is usually made of wood but may be made of any light metal as desired. An opening 11 is provided

2

for pivotally mounting the back binder 10 and is formed with a bushing 12 which is secured therein. This back binder thus may be mounted on the pivot pin 13 (shown in Fig. 3) to extend through the back wall 14 of the shuttle box designated generally 15 in this figure. The swell 16 of this back binder is in a position to be engaged by the shuttle as it enters the shuttle box. Some resilient means acting through the protection rod usually serves to press the back binder at its end distant from its pivot 13 so that it will guide the path of the shuttle as it enters the shuttle box.

A slot 20 extends from a point 21 adjacent the pivot inwardly and longitudinally of the back binder terminating in an opening 22 and provides a resilient movable longitudinally extending part 23 as a tongue extending along the inner portion of the binder adjacent to the swell 16 thereof. A cushioning surface 24 extends along this part 23 and also along the inner end portion of the back binder 25, which cushioning surface may be of leather as may be desired. The plate 26 is provided at this smaller end 25 to be pressed upon by the protection rod. Movement of the protection rod through this plate 26 serves to actuate this protection rod to lift the dagger when the shuttle is in position in the box.

In order to adjust this movable part or tongue 23 I have provided an abutment surface 27 (see Fig. 5) which is formed by inserting a threaded member 28 from the inner surface of the back binder and beneath the cushioning cover 24, such for instance as by means of a screw having a head 29 and slot 30 therein. This will be held securely in position by reason of the threads engaging the surrounding walls of the opening through which it extends. In order to engage this abutment I have provided a set screw 31

40 which extends through a hole 32 in the body and has threaded engagement at 35 with a plate 33 which is held on the outer surface of the back binder by means of screws 34. This threaded opening 35 threadingly receives set screw 31 45 which may be turned by a head 36 and may be held in adjusted position by the check nut 37 which engages the screw and bears against the plate 33. If it is desired to move the tongue part 23 further into the shuttle box, it is merely necessary to rotate the set screw 31 in a clockwise direction and then bind it in place by the check nut 37. This will force the portion 23 against its inherent resiliency into the position desired for fine adjustment of the surface of the back binder which engages the shuttle, to provide a greater area of contact between the binder and shuttle thus increasing the checking effect of the binder. This adjustment may also be made to compensate for wear on surface 24. 55 The adjustment is such that when the shuttle

is home in the box the face of the binder is substantially parallel to the face of the back of the box without undue compression of the leather 24. This permits the shuttle to easily get home.

I claim:

1. A binder for the shuttle box of a loom comprising a body having a swell and a longitudinal slot opening into the shuttle engaging side of the binder providing a longitudinally extending resilient tongue integral with the body of the 10 binder with a surface in continuation of the swell, and a threaded member extending through the body for engaging said tongue to adjust the position thereof relative to the body.

2. A binder as set forth in claim 1 wherein 15 said threaded member engages an abutment carried by said tongue to adjust its position relative to said body.

3. A binder as set forth in claim 1 wherein the face of the tongue is adjusted to a position 20 so that a part of its face will be parallel to the inside face of the box when the shuttle is completely home in the shuttle box.

4. A wooden binder for the shuttle box of a loom comprising a body having an opening at one end portion thereof for pivotally mounting the binder in the shuttle box, said body having 25 a longitudinal slot opening into the shuttle en-

gaging side of the binder adjacent to said opening providing a resilient tongue integral with the body and providing a surface for engagement by the shuttle, a threaded member extending laterally through said tongue providing an abutment, and a threaded member extending through the body in line with said abutment to engage the same to adjust the position of said tongue relative to said body.

WILLIAM LANGUIRAND.
